UNITED STATES PATENT OFFICE.

SAMUEL JOHNSTON, OF BROCKPORT, NEW YORK.

GRAIN-BINDER.

SPECIFICATION forming part of Letters Patent No. 239,048, dated March 22, 1881.

Application filed May 10, 1880. (Model.)

To all whom it may concern:

Be it known that I, SAMUEL JOHNSTON, of Brockport, in the county of Monroe and State of New York, have invented an Improvement 5 in Grain-Binders, of which the following is a specification.

My invention relates to grain-binding harvesters in general, but more particularly to the harvesters patented by me bearing date of December 16, 1879, and numbered 222,632 and 222,633; and it consists in the construction, arrangement, and operation of certain mechanism whereby the ends of the binding-cord are tied and the gavel bound, and which improvements 15 are fully and clearly set forth in the specification and referred to in the appended claims.

In the drawings, Figure 1 is a perspective view of my improved binding mechanism whereby the knot is tied. Fig. 2 is a plan of 20 same with the binding-frame taken away. Fig. 3 is a side elevation of same. Fig. 4 is a perspective view of the knot-tying mechanism proper. Figs. 5 to 8, inclusive, show various 25 positions of the looper and stages of the knot. Fig. 9 is a plan view of the holder and knife.

A is the binding-frame, which is rotated horizontally upon its axis B in the direction of the arrow. The end of the frame A is provided with two guides, B' and B², the guide B' laps 30 under B², thereby causing the cord to be thrown over the looper hook or jaws, as shown in Figs. 2, 3, and 5. The guide B' has a downwardly-projecting piece, b, which guides the cord up to the looper.

The cord-holder is constructed as follows: Pivoted at c, and working in bearings, is a bell-crank, C, carrying on the lower arm or heel-extension a ball-roller, C², and upon the other arm a curved piece, C', which is grooved 40 vertically. Situated directly in front of it is a spring, D, provided with fingers d, which rest in the grooves of the curved piece C'. The arm of the bell-crank is projected slightly beyond the part C', as shown at c', Fig. 3, 45 the object of which is to carry the binding-cord up between the two parts of the holder. The projecting side c', next to the looper, forms, with the edge piece, E, a shearing cord-cutter. This is shown in Figs. 4, 7, and 8.

50 Situated between the holder and guides is the looper F, which consists of two hooks or

jaws held tightly together. These jaws, in their rotation, form a loop in the cords between the gavel and holder, and then open, take the cords next to the holder between them, and, 55 after such cords have been severed by the cutter E c', draw the ends through the loop, and thereby make the knot. This is shown in Figs. 4, 5, 6, 7, and 8. The jaw f is attached to the shaft G, which rotates in bearings g g, and carries a bevel-wheel, G', upon the end opposite to the looper F. The jaw f' is secured to a sliding piece, H, which fits in a groove on the shaft G, the end projecting and in contact with the spring I, which always tends to force 60 the piece H toward the looper F, thereby keeping the jaws f and f' closed, unless opened by some opposing force. The piece H carries a roller, H', which, during the rotation of the looper in the act of forming the loop, strikes 65 the cam-dog J and opens the jaws f f', so as to take the cord between them, as shown in Figs. 4 and 7. The moment it passes the dog J the spring I, which is secured to the frame A, comes into play, closing the jaws tightly 70 upon the cord. The ends are now severed by the cutter E c', the looper rotates in the opposite direction, and when the roller H' strikes the incline j of the dog J said dog is pressed out, allowing the roller to pass to its original 75 position without opening the jaws. As soon as the roller has passed the dog the spring J' forces it back again against the pin j'. When the loop is formed as just described, and the ends of the cords are between the jaws and 80 being drawn toward said loop, the loop is pushed off and held above the looper by the finger a, while the jaws draw the ends of the cords through the loop, as shown in Fig. 8.

Pivoted to the binding-frame at K is a segmental cam-piece, L, which carries a cam-slot, L', and a rack, L². It is also provided with an arm, k, by which it is oscillated. The rack L² meshes with the bevel-pinion G' and causes the rotation of the looper F, first in one direction and then in the other. The part l of the cam-slot L' causes the cord to be thrown up into the holder, as shown in Figs. 4, 5, 6, and 7. The part between l and l' holds it there while the loop is being made and the ends 95 caught between the jaws f f'. The part l' then comes into play and causes the part c', 100

carrying the cords, to pass the shear-blade E and sever the cords, leaving the ends between the jaws.

Situated near the axis B is a cam-piece, M, 5 working upon a pin, N, and which is oscillated during the movement of the binding-frame by the rollers M' and M² striking the fixed cams T, T', and U. The cam-piece M carries a crank-pin, m', and a cam-slot, m. The pin m' is connected to the arm k by a connecting-bar, O. Working in the slot m is an anti-friction roller, p, upon the pin which connects the bars P and P'. The bar P is connected to an arm, Q, which is attached to and forms part of the 15 binding-frame A. The bar P' is connected to a bell-crank, R, oscillating upon a fulcrum at r, and carrying a spring-arm, R', which is provided with a horizontal arm, S, for the purpose of carrying the cords between the guides B' B² and over the looper, and then holding them firmly butted against the frame A, so 20 that no cord shall be withdrawn from the bundle during the tying of the knot. This is shown in Figs. 5, 6, and 7.

25 The operation is as follows: The end of the cord is placed between the spring-fingers d and grooved arm C'. It is then carried around the bundle by the band-carrying arm V, passed between the guides B' and B² by the arm S, 30 and again placed in the holder by the band-carrying arm. As the frame A rotates in the direction indicated by the arrow the roller M' strikes the cam T, oscillating the cam-piece M and causing the roller p to travel toward the 35 pin N, thereby quickly throwing the cords over the looper and holding them there by the piece S, as shown in Fig. 5. As the frame moves on, the pin m' is drawn back, thereby oscillating the segmental cam-piece L, which, 40 in turn, rotates the looper, making the loop, as shown in Fig. 6. During the formation of the loop the cord is drawn up into the holder, as before explained. The rotation of the frame A still continuing, the loop is formed, and the 45 roller H', striking the cam-dog J, opens the jaws f f', between which the cords pass, as shown in Figs. 4 and 7. The jaws then close upon the cords, and at this instant the part l' of the cam-slot in the segmental cam-piece L 50 comes into play, and the cord is severed by the cutter E c'. The roller M' has now passed the end of the cam T, and as the frame A still rotates, the roller M² strikes cam T, causing the cam M to oscillate in an opposite direction, 55 thereby rotating the looper also in an opposite direction, and at the same time the roller M' is thrown between the cams T and U. As the frame A continues its rotation the roller M' strikes the cam U, and the roller M², which is 60 not so long, passes over the cam T', thereby continuing the oscillation of the cam-piece M. As this takes place the looper is rotated, and the loop being brushed off and caught by the finger a, the ends of the cords are drawn 65 through said loop, as shown in Fig. 8. As

the rotation of the frame A is continued still further, the band-carrying arm is raised and all the parts return to their original position. The bundle is discharged from the platform, and as the ends of the binding-cord are still 70 held between the jaws, the knot is tightened and the ends dragged from the jaws. The machine is then ready for another gavel.

Having now described my invention, what I claim as new, and desire to secure by Letters 75 Patent, is—

1. The combination, with a cord-knotter, of a cord-clamp and a cord-holder, placed one on either side of the knotter, and operating mechanism by which the cord is positively and immovably clamped and held with slack or sag between the two clamping-points at the commencement of the knotting action. 80

2. The combination of a rotary reciprocating cord-knotter with a movable switch, 85 whereby one jaw is opened away from the other in the forward rotation of the knotter, but allowed to pass without being actuated upon the return movement.

3. A rotary reciprocating cord-knotter composed of two jaws, one of which is adapted to move to and from the other, in combination with a spring bearing upon the movable jaw to hold it against the other, and a switch or latch, which acts against a projection upon 95 the movable jaw in the forward rotation of the knotter, to cause it to open and receive the cord, but yield to the projection without actuating the jaw in the return rotation.

4. The combination of a rotary reciprocating cord-knotter with a spring-clearer, which 100 yields to the cord in the forward rotation of the knotter, but strips it therefrom in the return movement.

5. In combination with a stationary holder 105 and cutter, a rotary reciprocating cord-knotter and operating mechanism, by which the jaws of the knotter are brought by the forward rotation up to the cutter and holder just before the cord is cut, to seize the ends of the 110 cord, and then retracted by the return rotation to draw them through the loop.

6. The pivoted cord-holder having a working face concentric with its pivot and a heel-extension, in combination with the vibrating 115 plate provided with the cam-slot, substantially as and for the purpose set forth.

7. In combination with the pivoted cord holder and cutter, the cam acting upon a heel projecting therefrom, and so shaped as to impart two distinct onward movements thereto, the first to seize the cord and hold it while it is being looped and the second to sever it.

In testimony of which invention I hereunto set my hand.

SAMUEL JOHNSTON.
